UNITED STATES PATENT OFFICE.

DAVID McINTYRE, OF DETROIT, MICHIGAN.

TILE MACHINE.

Application filed March 9, 1922. Serial No. 542,236.

To all whom it may concern:

Be it known that I, DAVID McINTYRE, a citizen of the United States, and residing at Detroit, in the county of Wayne and State of Michigan, have invented a new and Improved Tile Machine, of which the following is a specification.

This invention relates to machines for the molding of building tiles from plastic material, and its object is to produce a machine of this character which operates continuously to carry a predetermined amount of plastic material to the mold, tamp the plastic mass and then eject the finished tiles. A further object of the invention is to provide means whereby the operation of the machine can be manually interrupted so as to prevent damage should the operators fail to supply the necessary plastic material or the proper pallets to support the tiles.

This invention consists in the details of construction illustrated in the accompanying drawings and particularly pointed out in the claims.

In the accompanying drawings, Fig. 1 is an elevation of the right side of the machine. Fig. 2 is an elevation of the left side of the machine. Fig. 3 is a front elevation of the machine. Fig. 3^a is a side elevation of one of the secondary tampers. Figure 3^b is a section on the line 3^b—3^b of Fig. 3. Fig. 3^c is a section showing the method of securing the cores in position. Fig. 4 is a central longitudinal section of the machine. Fig. 5 is a horizontal section on the line 5—5 of Fig. 4. Fig. 6 is a detail of an unlocking device for the pallet lifting mechanism. Fig. 7 is a vertical section of this lock on a plane parallel to that of Fig. 6. Fig. 8 is a horizontal section through the brackets for lifting the tampers on the line 8—8 of Fig. 11. Fig. 9 is a detail of the mechanism for controlling the tampers. Fig. 10 is a perspective of a pallet showing the bottom side thereof. Fig. 11 is an enlarged detail of the tamper lifting mechanism and the controlling device therefor. Fig. 12 is a vertical section through the supporting device for the feed box. Fig. 13 is a plan of the mold box with the cover plate removed. Fig. 14 is a perspective of the lower end of one of the main tampers. Fig. 15 is a longitudinal sec-

tion through one of the molds and through the pallet therein showing a pallet supporting bar. Figs. 16 and 17 are sections on the lines 16—16 and 17—17 of Fig. 3, showing an adjustable guide for the tamper bars.

Similar reference characters refer to like parts throughout the several views.

In the present machine previously mixed plastic material adapted to form building tiles is conveyed by a chute to the machine and at intervals this material is discharged into a feed box which is longitudinally movable from below the chute to above the mold or molds, it being understood that while the drawings show three molds for building tiles, the number and size of these molds may be varied as desired. The machine further embodies a tamping mechanism for ramming the plastic material into the molds after the feed box has carried a proper amount of material to the molds, and mechanism for elevating the pallets which form the bottoms of the molds after the plastic material has been properly tamped so that the pallets with the finished tiles thereon may be removed from the machine and replaced by others. It also embodies driving mechanism which is so connected and co-ordinated that the various steps necessary to the operation of the machine follow each other automatically, so that the only manual labor necessary is the removal of the pallets with the tiles thereon and the substitution therefor of new pallets. I prefer to so elevate the pallets above the mold box that a board may be slipped under the pallets and they with the tiles thereon carried away.

The frame of the machine shown in the drawings consists of upright posts 1 and 2 connected by horizontal channel bars 3 and frames 4 which are preferably castings, to whose forward ends are attached the brackets 5, as shown in Fig. 5, and to these brackets the front frames 6 which constitute the mold supports are connected. Extending upwardly from the rear ends of the front frames 6 and from the brackets 5 on the side frames 4 are upright frames 7 to which the upper plates 8 are connected. As shown in Fig. 11, these plates 8 extend rearwardly to constitute bearings for the main shaft 9. On this shaft 9 is a pulley 10 which re-

ceives the main driving belt 11. The shaft also carries a sprocket wheel 12 which receives a chain 13 which runs on the wheel 22 and by means of which the main counter-shaft 14 is driven. Secured to this main shaft 9 are a series of arms 15, one for each tamper, which arms carry rollers 16 at their outer ends adapted to engage the lower sides of the brackets 17, one of which is attached to each pair of tamper bars 18.

I have noticed that where the tampers of tile machines are connected to single bars, a very slight amount of looseness permits the tamper bars to turn and this results very often in the descending tamper head striking the sides of the mold and thereby not only losing the effect of the tamper but also injuring the parts of the machine. In the present case, two tamper bars 18 are provided for each tamper, which gives an extended bearing and permits of accurate adjustment so that the plastic material may be compacted adjacent the walls of the mold, where in many cases the finished tiles are left in a spongy condition.

The upper ends of the bars 18 of each pair are connected by means of a small cross bar 19 as indicated in Fig. 3^a. The rollers 16 on the arms 15 engage the lower sides of the brackets 17 which are attached to the bars 18, as shown in Fig. 8. The bars 18 of each pair are formed with notches to receive a key 20 which is carried in a slot 21 in the bracket 17, as indicated in Fig. 3. Bolts 23 extend through this key 20, through the brackets 17, and through the cap 24 so that each bracket 17 is rigidly secured to its respective pair of bars 18. Extending upward from the plates 8 on the upright frames 7 are two side bars 26 which carry guide members and which are secured at their lower ends to the upright bars 7 as shown in Fig. 3. These guiding members consist of plates 27 extending across between the upper ends of the uprights 26 and these plates carry the guide members 28 by means of the bolts 29 and the adjusting screws 30. As indicated in Fig. 2, there is one of these guiding plates 27 at the front and one at the rear of the lines of tamper bars 18 so that the entire group of bars can be properly adjusted relative to the mold. A second set of plates 27, similar to the first, is attached to the upright frames 7 just below the plates 8 and these carry a second set of guides. The sets of guides accurately control the positions of these tampers at all points of their strokes.

Extending across between the plates 8 in front of the side frames 7 is a shaft 32 on which a series of dogs 33 are pivoted. The upper ends of these dogs are tensioned toward the lifting brackets 17 by means of the springs 34 which are mounted between bars 35 carried by the plates 8. These bars

and springs are omitted in Fig. 2 for the sake of clearness. The shaft 32 is supported in sliding plates 36 (Fig. 2) which are adjustable by means of the screws 37 mounted in the lugs 38 on the side plates 8. As the tamper bars together with the parts attached thereto have considerable momentum, the brackets 17 move somewhat above the paths of the roller 16 so that when the dogs 33 swing into engagement below the lower outer corners of the brackets 17, as indicated in Fig. 11, the rollers 16 will not again contact with the brackets 17 until the dogs have been released. This eliminates much objectionable noise. As this excess of movement, however, is slight, it is desirable to have the dogs 33 adjustable so as to take up any wear which may occur between the dogs and the brackets.

Mounted in the plates 8 and extending across the lower ends of the dogs 33 is a shaft 40 which has mounted on it a series of cams 41, one for each dog 33, and adapted to swing the upper ends of these dogs out of the paths of the brackets 17. These cams 40 are so positioned on the shaft 40 that the tampers will come into action in a predetermined order so that the plastic material in the mold will be properly compacted. This order will be explained later on when the forms of the tampers are discussed.

Extending across the tops of the front frames 6 are two bars 45 on which the cores 46 are secured and on which the pallets are placed while the building tiles are being molded. The cores are preferably secured to the bars 45 by means of the bolts 47 and springs 48^a, as indicated in Fig. 3^c. These pallets consist of end bars 48, side bars 49 and intermediate bars 50. As indicated in Figs. 4 and 13, the cores 46 are in pairs so that the tile will be molded with a central wall connected to the side walls by bridge pieces which are formed by the concrete rammed into the transverse notches 52 in the cores. The cross bars 45 which support the pallets are preferably formed round at 53 where the parts of the pallet rest in order that any tile material which might pass the pallet and reach these bars will slide off instead of being held thereon as would be the case with a flat surface.

Attached to each side frame 6 of the front of the machine is a vertical guide bar 55, preferably round, on which a cross head 56 is slidably, and extending between these cross heads are cross bars 57 which support the pallet lifters 58 whose upper ends are forked as shown in Fig. 3, so as to constitute proper supports for the end bars 48 of the pallets. These pallets are within the spaces between the sides of the mold and the cores, but when these cross heads 56 are elevated the carriers 58 lift the pallets and the molded tiles thereon up above the mold and the cores therein.

so that the molded tiles may be carried away. I prefer that they shall be raised sufficiently high to permit a board to be slipped between the pallets and the cores so that the pallets and tiles can be carried away thereon. A cross bar 59 connects the two front frames 6.

The mold is formed of four stationary upright plates preferably in the form of channels. The side plates 60 are rigidly attached to the upper bars 3 of the frame and the front 61 and back 62 are rigidly secured to these side plates 60. As shown in Fig. 13, two dividing plates 63 are rigidly attached to the front plate 61 and back plate 62. Extending above the sides of the mold is a thin supporting plate 64 on which the feed box is slidable, this feed box being formed of a front member 65, rear member 66, as shown in Fig. 4, and two side members 67, as shown in Fig. 12. Attached to the side members 67 of the feed box are two brackets 68 which extend down and then upwardly at 69 and support the shafts 71 of the bearing rollers 70 which ride on the lower flange of the side bar 3 and thus support the feed box. A curved plate 72 may be attached to the upper flange of the side bar 3 and extend down outside the rollers 70 and thus prevent plastic material from getting into contact with these rollers and their journals. An angle bar 74 may be attached to the tops of the side and front channels which constitute the feed box for the purpose of preventing the plastic material from becoming lost.

The chute 75 which conveys the plastic material to the feed box may be supported by means of bars 76 which are attached at their front ends to the upright 7 and at their rear ends to the bearings 77 of the shaft 78. As shown in Fig. 4, a plate 79 extends across between the side channels 67 back of the rear channel 66 of the feed box so as to close the bottom of the chute 75 when the feed box is moved forward. It may be stated that the feed box is made of such size that the plastic material which comes down the chute and fills this feed box will properly fill the molds just described when thoroughly tamped. In case there is any excess of plastic material, it will be pulled back onto the plate 64 when the feed box is withdrawn.

Attached to the right end of the shaft 78 is a sprocket wheel 81 which connects to the main countershaft 14 by means of a sprocket chain 82. This sprocket chain may be kept at the proper tension by means of an adjustable idler 83 which may be mounted in any well known manner. The shaft 78 has a crank 84 on its left hand end which is provided with a pin 85 as shown in Fig. 2 and the sprocket wheel with a pin 86 as shown in Fig. 1. Connecting rods 87 extend from

these pins 85 and 86 to pins 88 carried by brackets 68, as shown in Fig. 12, and by these means the feed box is moved back and forth relative to the mold.

Pivoted to each bracket 68 on the feed box is an arm 90 which carries a pin 91 and roller 92 on its rear end, which roller bears against the upper flange of the side bar 3 of the machine and prevents the feed box from moving up away from the plate 64. This insures not only proper movement of the feed box but accurate measurement of the plastic material. As the plastic material in the feed box is pushed forward to its proper position over the mold, it will pack up against the rear channel or side 66 of the feed box and will therefore be most dense over the rear portions of the mold. In order to equalize the density of the plastic material in the feed box, I cause the shaft 78 to turn sufficiently to move the feed box back a short distance, say an inch or so, and thereby partially compact the plastic material which is against the front plate 65 of the mold box. The effect of this is a substantially even density of the plastic material in the mold after it is tamped.

Figs. 1 and 2 show the crank 84 and the sprocket wheel 81 when turned 180 degrees from the tamping position, but these figures clearly show the lead of the crank pins.

The mechanism for raising and lowering the pallets is shown in Figs. 4 and 5. A shaft 190 extends across between the rear posts 1 and on it is mounted a lever 192 provided with an opening 93 to receive a cam 94 on the shaft 95. The front end of this lever 192 is forked to produce the two arms 96 which carry a shaft 97 whose ends extend into wheels 98 that are slidable in the channels 99 to which the cross bars 57 are attached. This lever 192 may be counterbalanced by means of a weight 100 attached to the cable 101 which runs over the small pulleys 102 attached to the main frame of the machine.

Experience has shown that a speed of 66 R. P. M. is proper for the shafts 9 and 14; 22 R. P. M. for the shaft 95; and 2 2/5 R. P. M. for the control shaft 104. These shafts run constantly but the shaft 78 makes half revolutions intermittently. The shaft 104 makes one revolution for each cycle of the machine. The shaft 95 is driven from the shaft 14 by means of sprocket wheels 106 and 107 and a sprocket chain 108 between them. The shaft 104 is driven by the shaft 95 through the gears shown in Figs. 2 and 5. A pinion 109 is attached to the shaft 95 and meshes with a gear 110 on the short shaft 111 mounted in the plate 4 extending between the upright posts 1 and 2 on the left side of the machine. On this shaft 111 and connected to the gear 110 is

a pinion 112 which meshes with a gear 113 on the shaft 104. The reduction is nearly 10 to 1 as above stated.

Mounted on the shaft 104 is a disk 114 which has cam pins 115 and 116 extending from its right side, there being two of each of these pins, the pins 115 being opposite each other and the pins 116 being substantially ninety degrees apart. The disk 114 is formed with concentric rings of holes so that these pins may be given any desired location. On the shaft 14 is a sprocket wheel 117 which receives the chain 82 that drives the shaft 78 and this sprocket wheel 117 is attached to a clutch member 118 and a conical brake member 119 adapted to cooperate with the stationary brake member 120 rigid with the side frame of the machine. These parts 117, 118 and 119 are loose 20 on the shaft 14 and may be slid along the shaft by means of the lever 122 which is pivoted at 123 on a bracket 124 extending from the side of the machine. Attached to the outer end of the shaft 14 is a second 25 clutch member 125 with which the clutch member 118 is adapted to engage. Connected to the lever 122 is a transversely slideable bar 126 which is normally pulled toward the disk 114 by a spring 127. When 30 the inner end of this bar 126 is engaged by a cam pin 115, the bar is forced out against the tension of the spring 127 and the clutch members 118 and 125 engage, thus causing the rotation of the shaft 78 and 35 movement of the feed box in one direction. When the bar 126 has been forced outward a locking member such as shown in Fig. 7 holds it in its outward position. This locking member consists of a two part case 40 129 and 130 in which is mounted a spring 131 that normally holds the end of the rod 132 against the bar 126, which bar has a notch 133 indicated in dotted lines to receive the end of this rod 132. In the present case, the rod 132 is adjustably connected 45 to the link 134 by means of a turn-buckle 135, and this link 134 connects to a small lever 136 mounted on a pin 137 at the rear end of the machine, as shown in Fig. 1. The 50 sprocket wheel 81 carries two pins 138 adapted to engage the lever 136 and pull the pin 132 out of engagement with the bar 126 when this sprocket wheel has made one-half rotation, which permits the spring 127 to 55 disengage the clutch members. Immediately thereafter the spring 127 forces the brake members 119 and 120 into engagement and stops the shaft 78. It will be noticed that 60 the speed of the shaft 14 is very much greater than that of the shaft 104 so that the time occupied in moving the feed box in one direction or the other is only a fraction of the cycle of the machine.

The control of the lifting lever 192 is 65 similar to that of the feed box mechanism,

see Fig. 5. The cam 94 is loose on the shaft 95 but its hub is provided with a clutch member 139 which is adapted to mesh with the clutch member 140 slideable on but rotatable with the shaft 95. This clutch member 140 is movable by a lever 142 mounted on a pin 143 carried by a post 144. The clutch members 139 and 140 are normally disengaged by means of a spring 145. At the opposite end of the lever 142 is a bar 146 which is adapted to be moved longitudinally by one or the other of the cam pins 116 carried by the disk 114 to cause the clutch members 139 and 140 to engage. When this bar 146 has been moved outwardly by a cam pin 116, the clutch members 139 and 140 engage and the cam 94 begins to turn with the shaft 95. When this cam 94 has made a one-half rotation and elevated the pallet lifters, a pin 148 on a collar 149 shown in Fig. 6 engages the trip lever 150. This collar is mounted on the clutch member 139 and turns with the cam 94, and the trip lever is mounted on a pivot 151 carried by a plate 152 supported by a frame bar 153 (Fig. 5) that extends from the cross bar 155 of the frame to an end bar 156.

A link 154 is attached to the upper end of this trip lever and connects to the locking bolt 157 which engages the bar 146 in the manner shown in Fig. 6. Whenever a pin 148 strikes the lower end of the trip lever, the locking bolt 157 is withdrawn and the bar 146 released, permitting the spring 145 to disengage the clutch. The inner end of the control bar 146 is slidably supported by a second frame bar 158 similar to the frame bar 153. The pallet lifter will therefore be in its elevated position for one-fourth of the cycle of the machine during which time the finished tiles may be removed and fresh pallets substituted.

The operation of the tampers is also controlled by the shaft 104. The tampers are supported by the dogs 33 as above described and these dogs are moved to inoperative position by the cams 41 on the shaft 40. On the right end of this shaft is a crank arm 160 to which a rod 161 is pivoted. This rod has a yoke 162 at its lower end which slides on a hub 163 of a cam 164 on the right hand end of the shaft 104. This yoke is adjustable on the rod 161 by means of nuts 165, as shown in Fig. 9. A roller 166 on the pin 167 at the lower end of this yoke is engaged by the cam 164 to pull down the arm 160, and this cam has two steps 168 and 169, the first of which causes the shaft 40 to turn sufficiently to release the main tampers and the second to cause the release of the secondary tampers. The cams 41 are swung to inoperative position by means of the spring 170.

The tiles to be formed on this machine each consist of side, end and partition walls,

the side and partition walls being connected by bridge pieces at the top of the tile. The main tamper for each tile is shown in Fig. 14 and has side walls 172, end walls 174 and a partition wall 173 which correspond to similar walls of the finished tile. This main tamper is first released by the proper cam 41 and operates to compact the plastic material between the cores and between the cores and the sides of the mold. After a few operations of the main tampers, the secondary tampers are released. These are shown in Fig. 3^a and they are so positioned that they compact the plastic material along the outer sides of the cores. The operation of the main tampers continues through about one-fourth of the cycle of the machine while the secondary tampers 177 operate for about one-half of that time.

The mold may be changed as desired to produce tiles of different shapes and sizes. Where the length of the tiles is reduced below the longitudinal distance between the outer faces of the pallet lifters 58, the bolts 175 which secure the feet 176 of these lifters to the bars 57 may be removed and the lifters turned half way around. As these lifters are offset on their feet, as shown in Fig. 3^b, the over-all dimensions may be materially altered by this change.

The operation of the machine is controlled by a clutch member 180 slidable on the shaft 14, but rotatable therewith. The sprocket wheel 22 has a clutch member 181 adapted to engage the slidable clutch member which is movable by means of the bar 182. A shaft 183 extends from the front of the machine where it has a lever 184 at its front end, to the bar 182 where it has an upwardly extending arm 185 whose upper end extends into the slot 186 in the bar 182. The workmen at the front of the machine can therefore stop the main countershaft. A spring 187 normally holds the clutch 180 in engagement.

The details of construction and the sizes and proportions of the various parts may all be changed by those skilled in the art without departing from the spirit of my invention as set forth in the following claims.

I claim:

1. In a tile machine, the combination of a rigid tile mold, a plate mounted on the mold and extending rearwardly and having openings to permit the passage of plastic material, a feed box slidable on said plate, a chute for plastic material extending downwardly to said plate and spaced therefrom sufficiently to permit the feed box to move underneath the lower end of the chute to be filled and to move forwardly over the mold to discharge its contents, and a plate 65 extending rearwardly from the feed box to

close the lower end of the chute when the feed box is in its forward position.

2. In a tile machine, the combination of a tile mold, a feed box adapted to convey a proper amount of plastic material to the mold, a chute to fill the feed box, a shaft mounted in the machine, cranks mounted on said shaft, connecting rods extending from the cranks to said feed box, and means to turn the shaft through one-half rotation to move the feed box to position over the mold, said means causing the feed box to begin its return movement before it comes to rest over the mold so as to compact the plastic material at the front end thereof.

3. In a tile machine, the combination of a mold, means to convey a proper amount of plastic material to the mold to form a tile, and tampers to compact the plastic material, one of said tampers being formed of side, partition and end walls and the other tampers of the set being formed with cross heads adapted to compact the material within the space enclosed by said walls of the first named tamper.

4. In a tile machine, the combination of a mold, a pallet adapted to be placed in the bottom of the mold, a lever to elevate said pallet, a shaft and a cam loose thereon adapted to elevate said lever, means to drive said shaft, a control shaft, a clutch to connect the cam to the shaft on which it is mounted, and means on said control shaft to cause the operative engagement of said clutch.

5. In a tile machine, the combination of a mold, a pallet adapted to be placed in the bottom of the mold, a lever to elevate said pallet, a shaft and a cam loose thereon adapted to elevate said lever, means to drive said shaft, a control shaft, a clutch to connect the cam to the shaft on which it is mounted, means on said control shaft to cause the operative engagement of said clutch, and means on said cam shaft to cause the clutch to disengage.

6. In a tile machine, the combination of a mold, feed box adapted to carry a proper amount of plastic material and tampers for compacting the plastic material, each of said tampers comprising a pair of vertical bars and a tamping head at the lower end of said bars, and adjustable means mounted on said machine and spaced apart vertically and movable horizontally to guide said tamper bars.

7. In a tile machine, the combination of a mold, cores for said mold, cross bars mounted in said machine adapted to support said cores, and pallets adapted to be placed within the mold to receive the plastic material, said cross bars having rounded upper surfaces on which said pallets may rest.

8. In a tile machine, the combination of a mold, cross bars beneath the mold, pallets adapted to be placed on the cross bars in the bottom of the mold, vertical guides adjacent said mold, a frame vertically slideable on said guides, forked pallet lifters attached to said frame and adapted to move the pallets vertically up and out of the mold, a lever pivoted in said machine, means to raise and lower said lever, a horizontal shaft mounted in the front end of said lever, and rollers on the ends of said shaft adapted to engage said frame to raise and lower the same. 10

DAVID McINTYRE.
